[57] CLAIM

The ornamental design of the computer printer, as
shown and described.

DESCRIPTION

FIG. 1 is a top, left perspective view of a computer
printer, showing our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines in FIGS. 1 and 5 are for illustrative
purposes only and form no part of the claimed design.
